DESIGN FOR A JEWELRY FINDING

Fritz Regelmann, Cranston, R. I., assignor to Carl-Art, Inc., Providence, R. I., a corporation of Rhode Island

Application March 4, 1940, Serial No. 90,674

Term of patent 7 years

To all whom it may concern:

Be it known that I, Fritz Regelmann, a citizen of the United States, residing at Cranston, in the county of Providence and State of Rhode Island, have invented a new, original, and ornamental Design for a Jewelry Finding, of which the following is a specification, reference being had to the accompanying drawing, constituting a part thereof.

Fig. 1 is a side elevational view, slightly in perspective, of a jewelry finding showing my new design;

Fig. 2 is a bottom plan view.

I claim:

The ornamental design for a jewelry finding, substantially as shown.

FRITZ REGELMANN.
